UNITED STATES PATENT OFFICE

99,257

DESIGN FOR A COMMEMORATIVE EMBLEM

Marshall Rowland, Dallas, Tex.

Application March 16, 1936, Serial No. 61,669

Term of patent 3½ years

To whom it may concern:

Be it known that I, Marshall Rowland, a citizen of the United States and a resident of Dallas, in the county of Dallas and State of Texas, have invented a new, original, and ornamental Design for a Commemorative Emblem, of which the following is a specification, reference being had to the accompanying drawing, forming a part thereof.

In the drawing:

I claim:

The ornamental design for a commemorative emblem as shown.

MARSHALL ROWLAND.
